INTERNAL RIBBED MANIFOLD FOR
MULTICYLINDER INTERNAL-COMBUS-
TION ENGINESArthur F. Milbrath, Milwaukee, Wis., assignor to
Wisconsin Motor Corporation, Milwaukee, Wis.,
a corporation of Wisconsin

Application February 16, 1949, Serial No. 77,022

9 Claims. (Cl. 123—52)

1

This invention relates to an internally ribbed manifold for multi-cylinder internal combustion engines.

It is an object of the invention to render combustion in the several cylinders more uniform, regardless of engine speed, by effecting a more uniform distribution of the combustible mixture as between the several cylinders throughout the range of engine speeds, and even to make possible uniform combustion of lowergrade fuel oils than can be employed without the benefit of the present invention.

The invention can best be explained by reference to the accompanying drawings, wherein:

Fig. 1 is a view in end elevation of a V-type engine equipped with a manifold embodying the invention, portions of one of the cylinder blocks and certain of the manifold passages being broken away.

Fig. 2 is a view in longitudinal section through a manifold embodying the invention.

Fig. 3 is a detail view taken in cross section on the line 3—3 of Fig. 2.

Fig. 4 is an inverted plan view of the manifold shown in Fig. 1 and Fig. 2.

Fig. 5 is a fragmentary detail view of a modified embodiment of the invention as it appears in a longitudinal cross section through the manifold or conduit, the ribs being shown in plan.

The engine which has been equipped for the purpose of exemplification with a manifold embodying the invention, happens to be a V-type, four-cylinder engine having angularly divergent cylinder blocks 6 and 7. The manifold distributing ducts 8 and 9 respectively lead to the cylinders, and the exhaust gas collecting ducts 10 and 11 open therefrom in accordance with conventional practice. While the present invention is not concerned specifically with the exhaust arrangements, it may be noted that the intake manifold 12 and the exhaust manifold 13 may conveniently be cast in one piece as is best shown in Figs. 2 and 3. The carburetor 15 is connected centrally to the intake manifold 12 by means of the coupling flange 16. The exhaust manifold 13 is tapped at 17 to receive the exhaust pipe 18.

The particular carburetion shown involves the use of an updraft carburetor, but the invention is by no means limited thereto. In any instance where the carbureted air must be divided, as between the manifold branches 19 and 20, leading to the respective cylinder blocks, it has been noted that there is considerable irregularity of flow. The turbulence within the manifold

2

fluctuates in accordance with the speed and the grade of fuel and, frequently, independently of either of these factors. In consequence, unatomized and unvaporized droplets of fuel such as commonly are found clinging to and advancing along the manifold wall, whenever they are acted upon by air currents sufficiently strong to move them, may, as a result of erratic turbulence, be thrown at one time principally into one of the manifold branches, and at another time principally into a different manifold branch, overloading first one cylinder, and then the other, and making impossible any correct adjustment of the carburetor which will keep the cylinders firing equally and with uniformity.

What has been said with regard to the propulsion of unatomized droplets of fuel is also true of the heavy ends of the fuel vapors which, even though they be free of the walls, are caused by erratic turbulence to flow one way or the other into one or other of the manifold branches in such fashion as has heretofore defied any attempt at control.

I have found that erratic turbulence can be almost entirely controlled through the use of vanes which desirably take the form of ribs cast internally on the manifold wall. These vanes give definite direction to the currents of carbureted air and, being located on the wall surface, they tend to provide well-defined accelerated currents of air flow which pick up and move with substantial regularity the droplets whose movement has heretofore defied regulation. In accordance with the preferred practice of the invention, I locate these vanes at the point where the air supplied by the carburetor 15 is divided between the manifold branches 19 and 20. Thus, one of the vanes 21, located on the far wall of the manifold as viewed in Fig. 2, commences at the manifold inlet and curves arcuately along the far wall toward the manifold branch 20. The other vane 22, located on the near wall of the manifold as viewed in Fig. 2 (only a fragment of such wall being there illustrated), begins at the same point and, directly opposite the curved vane 21, curves toward the manifold branch 19.

While the disposition of these vanes at this particular point where the manifold branches is a preferred practice, it is also possible either to use additional vanes, or to locate the vanes in a straight length of manifold passage, both of these features being illustrated in Fig. 5, where a straight length of manifold passage is shown at 23 with helical vanes 24 and 25 on one side of the passage, and helical vanes 26 and 27 on the

opposite side of the passage. In this view, the vanes or ribs have been exposed by cutting away the top half of the manifold to expose the vanes. It will be noted that each of the vanes runs out or tapers to merge with the wall of the manifold at its ends, reaching maximum thickness intermediate its ends.

It is believed that in the straight wall passage, the action of the ribs or vanes is slightly different from that produced where they are located at the point of air division. In both instances, it appears that the vanes pick up and concentrate droplets which are being propelled by the air currents along the inner wall of the manifold, the vanes also concentrating in the angle between the vane and the manifold air currents which give a sufficient impulse to the droplets or stream of fuel, either to complete the atomization or vaporization thereof, or to entrain them for more rapid and more uniform movement to the cylinder for combustion. In the use of the vanes in Figs. 1 to 4, the vanes have the additional advantage that their curved form and symmetrical disposition tend to divide the charge more uniformly, assuring the delivery of half of the charge into one branch of the manifold, and the other half in the other with considerable uniformity and regularity, regardless of engine speed. In any event, tests as to uniformity of combustion, supplemented by visual inspection of mixture flow through manifolds with transparent walls, have indicated that with the vanes there is substantial uniformity at all speeds, whereas, without the vanes, there is erratic turbulence with particular variation when engine speed varies. It has also been demonstrated that an engine which will operate satisfactorily only with a good grade of gasoline when its manifold is not equipped with the vanes or ribs here disclosed, can be made to operate with equal or greater satisfaction on No. 2 furnace oil when the manifolds are ribbed or vaned interiorly in accordance with the present invention.

I claim:

1. As a new article of manufacture, an internal combustion engine manifold comprising a tube having opposed wall surfaces and opposed series of internally projecting ribs along said opposed wall surfaces, each such rib extending helically along the wall of the manifold for less than a full circumference of the tube.

2. As a new article of manufacture, an internal combustion engine manifold comprising a tube having substantially uniform cross section and provided interiorly with a plurality of internally projecting ribs each comprising a curved protuberance extending helically along a wall of the manifold for less than a full circumference of the tube, each rib having maximum thickness

intermediate its ends and tapering towards its ends.

3. As a new article of manufacture, an engine manifold which comprises a conduit interiorly provided with ribs axially inclined said ribs being discontinuous and converging toward and merging with the contours of the interior of the manifold at both ends of the respective ribs.

4. As a new article of manufacture, an engine manifold which comprises a conduit interiorly provided with discontinuous ribs axially inclined and merging at spaced intervals with the contours of the interior of the manifold and symmetrically disposed in opposite sides of the conduit.

5. A manifold as defined in claim 4 in which the manifold conduit comprises an inlet and a pair of branches having a juncture at the inlet, the ribs being disposed adjacent the said juncture and oppositely inclined toward the respective branches.

6. As a new article of manufacture, an internal combustion engine manifold comprising integrally an inlet and a pair of oppositely extending branches, the inlet having opposing walls between which the branches open, and the said walls being integrally provided with arcuately curved and mutually opposite ribs respectively curving toward different branches.

7. A manifold comprising a conduit integrally provided on opposite walls with opposed multiple ribs of generally helical discontinuous form.

8. The manifold of claim 7 in which the ribs have maximum thickness intermediate their ends and merge with the conduit at such ends.

9. As a new article of manufacture, an internal combustion engine manifold comprising an inlet and a pair of balanced oppositely extending branches, each of said branches being provided with an equal number of service connections to an equal number of cylinders, a plurality of rib-like protuberances each extending inwardly from the walls of the inlet, one of said protuberances extending into one of the branches, and another extending into another branch whereby to divide gaseous flow from the inlet to the respective branches.

ARTHUR F. MILBRATH.
